ASSIGNORS OF ONE-THIRD TO ERNEST H. GILBERT, OF MORGANTOWN, WEST VIRGINIA

TRACKLESS MINE MOTOR

Application filed February 24, 1928. Serial No. 256,665.

The present invention relates to what may be conventionally designated as a trackless mine motor, that is, a new type of electric motor propelled vehicle, such as can be conveniently employed for conveying various kinds of mine appliances and machinery, through various headings, wherein coal is usually transported on conveyors and where the laying of tracks is unnecessary.

10 The invention has more particular reference to an especially constructed vehicle, but not necessarily adapted for use in mining, shown and described in our co-pending application Serial No. 203,011 filed under date of July 2, 1927, covering what is designated as a concentrated pocket system of attacking and retreating long wall.

It is well known that the floors of these headings are usually quite rough, and thickly covered with small particles of coal dust and dirt, thus producing an effective traction surface for the various types of vehicles which have been devised to take the place of track cars.

25 In view of the difficulties, various kinds of traction devices have been provided, these being of the type commonly known in the trade as tracklaying vehicles.

Because of the peculiarities of the coal dust, 30 the driving drums and chains become clogged with this dirt. The result is that they jam and refuse to work. In some instance, the chains, being under unusual strain, become disrupted and then useless.

35 With the foregoing in mind, we have conceived of a self-propelled car such as can be conveniently manipulated in various kinds of headings, the same being characterized by an especially designed platform, dependable control devices, and improved tracklaying traction devices.

A particular feature of the invention to be emphasized is the construction of the tracklaying devices, these being characterized 45 by the presence of dependable driving drums

of an unusual kind, and substantially self-cleaning endless traction chains, such as are not likely to become clogged with coal dirt.

Other features and advantages of the invention will become more apparent from the following description and drawings. 50

In the drawings:

Figure 1 is a side elevation of a car constructed in accordance with the present invention.

Fig. 2 is a top view showing the interior of the body.

Fig. 3 is an enlarged detail view of one of the driving drums, and complemental portions of the improved chains associated therewith. 60

Fig. 4 is a view at right angles to Fig. 3, the sections being on the line 4-4 of Fig. 3.

Fig. 5 is a central vertical section thru one of the drums, and

Fig. 6 is a perspective view of one of the especially designed traction lugs. 65

In the drawings, the reference character 7 designates generally the body of the car, which is of any appropriate construction. 70 This is of course provided with suitable closures mounted on a sturdy base. The base includes extension platforms 8 at opposite ends, whose under sides are beveled upwardly and outwardly to permit them to ride over obstructions in the path of travel, and to prevent the ends of the tracklaying devices from abruptly striking obstacles. These platforms are in the top plan configuration as shown in Fig. 2, to aid in guiding the car, 75 and they are provided with appropriate couplings 9.

If desired, electric lights 10 may be mounted on opposite ends of the car in any suitable place. Located beneath the base and mounted thereon, in any convenient way, are especially constructed tracklaying structures. Since the construction is the same on each side, a description of one will suffice for both.

Each tracklaying structure is composed of 80 85 90

5 a series of drums 11 as shown in Fig. 3, graduated in size from the center toward the end, to provide the usual configuration, and to permit proper cooperation of the end portions of the tracklaying structure with the inclined under sides of the platforms 8. Each drum is provided with outstanding journals as at 12, as shown in Fig. 4, the opposite ends of which are mounted for rotation 10 in bearings in suitable portions of the base as shown in Figure 2. A side bar 13^a extends along the outside of each set of drums and connects the journals 12 as shown. These outside bars may be connected to the main 15 frame in any suitable manner.

20 As shown in Fig. 4, the drum in each instance is comparatively wide, and includes a centrally disposed circumferential rib 13, whose marginal edges are beveled as at 14 and provided with pairs of opposed grooves 15. Located on opposite sides of the ribs are 25 rows of teeth 16. Cooperating with each row of teeth is an endless traction chain 17 which is composed of lugs 18 connected together by links 19.

30 The links have their marginal edges beveled and the inner beveled edges cooperate with the correspondingly beveled edge 14 of the rib 13, as shown in Fig. 4. The links 19 are constructed for cooperation with the teeth 16. The lugs 18 are of a construction shown in Fig. 6, and reference being had to this view, it will be seen that each lug comprises a substantially rectangular block having a truncated pyramidal portion 20. In addition, a tapered hole 21 is formed completely through the lug, as shown in Figure 3.

40 In connection with this hole, it is observed that as the chains travel over the drum, considerable coal dirt is permitted to accumulate between the surface of the drums and the chains. However, as the lugs come down upon the surfaces of the drums, the dirt is forced out through the holes 21. Thus the chains are 45 substantially self-cleaning.

50 Moreover, dirt such as might otherwise be jammed between the chain links and the central rib 13 is ejected out through the openings or grooves 15 in the rib. With this arrangement, breakage of the chains is practically prevented and efficient traction is assured. Thus we have a pair of duplicate tracklaying devices, where in each tracklaying device is composed of graduated drums having inner 55 and outer rows of teeth for cooperation with the individual chains.

60 Each chain is characterized by its specially designed link cooperating with the beveled central rib and connected to especially constructed traction lugs, the lugs and rib being constructed to aid in ejecting coal dirt to insure efficient traction.

65 In practice, a controller box 22 is arranged within the car body in advance of the operator's seat 23. On opposite sides of this seat,

70 we find operating levers 24 connected with control rods 25 leading back to bell cranks such as serve to operate the cone clutches 26. We have a dual clutch arrangement here, which permits either clutch to be operated. Thus, one tracklaying device can be operated, while the other one will be permitted to remain still to permit steering in a well known manner.

75 In addition, there is an electric motor 27 which receives current from a source of supply not shown. Moreover, this motor has a dual pinion arrangement wherein the pinions are included in gearing trains serving to impart power to the tracklaying devices on opposite sides of the base.

80 After considering the detailed description in association with the drawings, it is believed that a clear understanding of the construction, its use, and advantages, and operation of the invention will be had. Therefore, a more lengthy description is thought unnecessary.

85 Having thus described our invention, what we claim as new is:

1. In a mine motor vehicle of the class described, a base, and tracklaying traction drives carried by said base and located on opposite longitudinal sides thereof, each drive comprising a plurality of drums, each drum having a central rib provided with beveled marginal edges in which grooves are formed, circumferentially spaced annular rows of teeth on the surface of the drum and located on opposite sides of the rib, and pairs of endless chains trained over said drums, and co-operating with said ribs and teeth. 90

95 2. In a mine motor vehicle of the class described, a base, tracklaying traction drives mounted on said base, operating means for said drives also mounted on said base, each drive comprising a plurality of drums, each drum being relatively wide and being formed with a centrally located circumferential rib on opposite sides of which are annular rows 100 of driving teeth, the marginal edges of the rib being beveled and provided with grooves disposed radially and opening through the flat tread portion of the rib, chains trained over said drums, and cooperating with said teeth and said ribs, said chains being composed 105 of links connecting a multiplicity of lugs, and each lug being provided with a passage therethrough for dirt. 110

115 3. In testimony whereof we affix our signatures.

120 WILLIAM H. COBURN.
CHARLES KIERNAN.
